UNITED STATES PATENT OFFICE

EDWARD L. DUNN, OF WORCESTER, MASSACHUSETTS.

ELEVATOR-OPERATING SYSTEM.

987,673.

Specification of Letters Patent. Patented Mar. 21, 1911.

Application filed July 2, 1908. Serial No. 324,384.

To all whom it may concern:

Be it known that I, EDWARD L. DUNN, a citizen of the United States, residing at Worcester, in the county of Worcester and 5 State of Massachusetts, have invented a new and useful Elevator-Operating System, of which the following is a specification.

My invention relates to a dumb-waiter or elevator operating apparatus intended to be manipulated from a single station in such a manner as to provide for giving all necessary motions to the car; to provide ample safety devices to prevent the car from running away; to provide means for preventing 10 the operation of the car when any of the doors of the well are open; to provide a floor indicator having a traveling pointer or the like, representing the car, and showing at all times the position of the car, said 15 indicator having means for automatically stopping the car when it reaches its predetermined destination, and also when it reaches the top or bottom of the well. Further to provide an automatic mechanical or 20 solenoid brake applicable in an efficient manner when the car is to be stopped; to provide a signal lamp or the like to show clearly whether the car is in motion or not, and also to show when anything about the 25 apparatus is out of order, so as to prevent the operation of the car; to provide a simple controlling device adapted to be located in position convenient to the floor indicator, and having ample safety arrangements; to 30 provide an improved main switch, improved direction solenoid switches, and an improved rheostat; and especially to so construct and combine all these and other co-operating features as to effect a great economy in space 35 40 over the one point electric control elevators and dumb waiters heretofore constructed; and also to secure these results in such a manner that the duty of the machine can be increased without unduly increasing the size 45 of the operating parts and controlling mechanism.

Further objects and advantages of the invention will appear in the course of the subjoined description.

50 Reference is to be had to the accompanying drawings which illustrate a preferred embodiment of my invention, and in which—

Figure 1 is an elevation showing a por-

tion of the well with car-operating mechanism and controlling box. Fig. 2 is a diagrammatic view illustrating a form of motor winding and rheostat connected with the motor. Fig. 3 is a diagrammatic view showing wiring. Fig. 4 is a plan of the controlling devices situated at the motor. Fig. 5 is a side view of the main switch and brake. Fig. 6 is a bottom plan view of certain contact devices connected with the main switch. Fig. 7 is a side elevation of one of the direction solenoid switches. Fig. 8 is a 65 plan of the indicator on an enlarged scale, parts appearing in section. Fig. 9 is a sectional view of the same on the line 9—9 of Fig. 8. Fig. 10 is a plan of the rheostat. Fig. 11 is a side elevation of the same, parts 70 appearing in section. Fig. 12 is a front elevation of the operating or controlling box with parts broken away to show interior construction, an annunciator box, and signal lamp also being shown. Fig. 13 is a side elevation of the same, parts being broken away and shown in section. Fig. 14 is a fragmentary front elevation with parts in section on an enlarged scale showing portions of the same. Fig. 15 is a central sectional 75 view on an enlarged scale of parts in the operating box. Fig. 16 is a perspective view of a friction disk employed in the operating box. Fig. 17 is a perspective view of a lug on the operating shaft. Fig. 18 is a perspective view of a bell-crank shown in Fig. 15, and Fig. 19 is a side elevation of a portion of the car and a door-locking device. mechanism on the car for operating the door-locking-device also being shown.

90 The general nature of the invention will first be described with special reference to Fig. 1.

The system comprises, as usual, a hoisting machine A, an operating box B, which may 95 be located apart from the machine in any convenient position, and also controlling mechanism connected with the machine. The hoisting machine or winding mechanism may be of the well-known worm-gear 100 type. Attached to it, or otherwise conveniently located is a slate a on which are arranged switches and other devices for controlling the motor connected with the winding mechanism. This slate is preferably 105 mounted in horizontal position above the

motor, and carries in the present instance, a main reversing switch G controlled by solenoids, direction switches C actuated by two small solenoids, several fuses D', D², D³, 5 etc., a floor indicator K which is driven by a sprocket chain a' or the like from the drum-shaft, a solenoid actuated rheostat, and also if desired, the line switch, (not shown in Fig. 1). In addition to these features, the system embraces a signal light I 10 to indicate the condition of the car, and its operating mechanism, a door locking device for each door, and means on the car for unlocking the door at which the car is to stop, leaving all other doors which it 15 passes locked at all times. An ordinary announcing system is also provided embodying a box in the basement or any convenient place by means of which a person at 20 the floor at which the car is to stop will indicate to the operator of the system the floor to which the car is to be sent. Of course, at each floor there is a push button which is pressed when the car is wanted 25 and which shows by the annunciator where the car is to be sent.

The duty of the main switch is to hold its own solenoid in circuit; to run the motor in either direction; to release the brake with 30 which the motor is provided; to cause the signal light to burn at full candle power; to energize the rheostat solenoid; to shunt the direction-switch solenoids out of circuit; to feed a lock solenoid under certain conditions, and energize a car solenoid, which will be described below. All of these duties with the exception of controlling the motor and releasing the brake are performed by auxiliary switches located below the main 35 switch solenoids. The duty of the direction solenoid switches is to energize the main switch solenoids, provided the well-room doors are all closed, and if not, to remain in circuit until the doors are all closed, and, at 40 45 the same time, feed the lock solenoid so as to prevent the pointer of the operating box from being reversed. The duty of the rheostat is to protect the motor from a rush of current, and in starting, to accelerate the same until full speed is reached, those being 50 the ordinary duties of such a rheostat. The duty of the floor indicator is to rotate or otherwise move a pointer when the car moves, the rotation of the pointer being proportionate to the travel of the car, and indicating at all times the position thereof; also 55 to make a contact or close a switch as the car passes each floor, and if the operating box pointer has been placed in position opposite the numeral indicating any particular floor, to stop the car at that floor.

The operating box B which has been mentioned, is placed in position convenient to the announcing box and to the signal light. 60 65 This box contains in addition to these fea-

tures, a lock actuated by a solenoid, fed first by the direction of switch solenoids, and later by the main-switch, two small direction switches, a contact for each floor, and a movable pointer.

To start the machine, the pointer is moved to the contact representing the floor to which the car is to run. Mechanism is provided for preventing the car from starting until the pointer has moved at least one space 75 onto a point indicating the next floor. When the pointer is moved this distance, five distinct operations take place in the operation box. First, the circuit which causes the machine to stop is opened; second, a new stop circuit is closed or made; third, the direction switch closes; fourth, the lock solenoid lifts its plunger to prevent the pointer from being reversed; and fifth, the direction switch opens. To describe these operations more 80 specifically, it may be stated that when the pointer is moved onto a contact indicating another floor than the floor at which the car is then stopped, the direction switch in the operating box is closed, and the corresponding direction-solenoid-switch mentioned above as being part of the controlling mechanism at the machine, operates. The small solenoid in the operating box, called the lock-solenoid, also operates to 85 prevent the pointer from being reversed, and, at the same time, to open the direction switch which has just been closed. Now, provided all the doors in the well are closed, the main switch operates, the machine starts, and the lamp burns at full candle power. On the other hand, if a door is open, the lamp remains extinguished, and the direction solenoid switch at the machine and the lock solenoid remain in circuit, thus locking 90 the pointer against a reverse movement. If the door is now closed, the machine will start, the direction solenoid switch is then energized and the lock solenoid remains in circuit until the machine stops. This is indicated by the signal lamp changing from 95 full candle power to half candle power. The car is forced to follow the pointer of the operating box. If the pointer is once moved 100 a floor space, it can be carried onto the limit of its travel, but it cannot be moved in the opposite direction until the machine has sent the car to the floor indicated by the pointer. If the current is broken by the 105 forcing open of a door while the car is in motion, the car is instantly and automatically caused to stop. In such a case the car is not at the floor indicated by the pointer, and if the pointer is then moved one floor space 110 in a direction opposite to that along which it was moved to send the car in the direction in which the latter had been moving, the car would go to the limit in that direction 115 where it would be stopped naturally by the automatic which is provided. A second 120 125 130

movement of the pointer in the same direction would have no result, as the switch in that direction cannot receive current, the automatic being open. The first movement 5 in the other direction starts the car, and the car will then stop correctly with the pointer again.

The general scheme of operation will now be described with special reference to the 10 diagrammatic representation of the wiring in Figs. 2 and 3. The mains are designated by the plus and minus signs and are connected by a switch with the several wires for operating the different devices employed.

15 Referring first to Fig. 3, it will be observed that the plus main is connected with two conductors, one of which supplies current to a down automatic or limit stop A' and an up automatic or limit stop A^2 . Each of 20 these automatics is a part of the floor indicator and is intended to break the circuit when the indicator shows that the car is either at the top or bottom of the well. Each one is in constant communication by means 25 of a conductor with a direction switch in the operating box B, the two direction switches being designated by B' and B^2 . At this point, under normal conditions, the current is broken, and, therefore, the wires leading 30 to the direction switches are dead. In like manner, the two automatics are constantly connected by conductors with a pair of movable terminals which are a part of the two direction solenoid switches C' and C^2 , respectively. 35 These switches are on the slate, and in their normal condition, the terminals are out of contact with their conductors, and consequently, the current is normally broken at this point.

40 By reference to Fig. 7, it will be seen that each of the switches C' and C^2 comprises a solenoid c^3 having a core c^4 which carries a horizontal bar c^5 , and which carries a pair of conductors c^6 and c^7 electrically connected together. 45 When the solenoid c^3 is not supplied with current, the bar c^5 is down and the terminals c^6 and c^7 are out of contact with a pair of terminals c^8 and c^9 , but when the current is supplied to the solenoid, 50 and the bar is thereby raised, the terminals c^6 and c^7 are brought into contact with the latter. Therefore, as the second conductor leading from either of the automatics A' or A^2 is permanently connected with the terminals c^6 and c^7 of one of the switches C' or C^2 the excitation of the corresponding solenoid c^3 puts the automatic into communication with both of the terminals c^8 and c^9 of the corresponding switches. The terminals c^8 on the two direction solenoid switches are in communication with the corresponding solenoid to feed current thereto, 60 and also with a pair of terminals b^3 and b^4 on the direction switches B' and B^2 , respectively. The purpose of these will be ex-

plained below. The other side of each of the two solenoids c^3 is connected in parallel with each other and in series with a fuse D' which is in communication in series with the lock solenoid E . This solenoid is in communication with a resistance F through which the current passes to the negative side of the line. It will be seen, therefore, that when either of the switches C' or C^2 is energized, current will be transmitted from one side of 70 the line through the corresponding automatic A' or A^2 to the solenoid which is energized, through the fuse D' , the lock solenoid E , and the resistance F to the other side of the line. The way in which this 75 state of affairs is brought about will be described below.

The terminals c^9 on the direction solenoid switches are in constant communication with two main switch solenoids G' and G^2 which 80 control the operation of the car. These solenoids are connected at their other terminal, in parallel with each other and in series, with a fuse D^3 . This fuse has a conductor passing through a series of door 85 switches H' , H^2 , H^3 , H^4 and H^5 arranged in series and then communicates with the conductor leading to the negative side of the line between the lock solenoid and the resistance F . Therefore, the operation of 90 either of the switches C' and C^2 will supply current to one of the solenoids G' and G^2 , provided the door switches are all closed. These door switches, as will be explained below, are so arranged that when the doors in 95 the elevator well are closed, the switches will be closed and the opening of one of the doors will open the switch and consequently cut out the main switch solenoid which is at that time in operation, and prevent either 100 of these solenoids from being again connected until all the doors are closed.

105 After one of the direction solenoids is operated it is automatically cut out or short-circuited, in a manner to be described below, and in order to keep the main switch solenoids in operation after the direction solenoids are automatically cut out, each of the main switch solenoids is provided with four insulated terminals g^8 , g^4 , g^3 and g^6 . The 110 terminals g^3 below the two solenoids are each connected with the conductor giving current to the opposite main switch solenoid; consequently, if the main switch solenoid G' is energized, the terminal g^8 on the 115 other solenoid will be alive. The terminal g^4 in each case is connected with the conductor feeding from the opposite automatic A' or A^2 to the opposite terminal c^6 , so that if current is being supplied through either of 120 the automatics A' or A^2 , the terminal g^4 on the opposite main switch solenoid is alive. The two terminals g^6 are connected together, and the same is true of the two terminals g^5 . The terminals g^8 are in constant connection 125

with the conductor which connects the two solenoids C' and C² with the fuse D'

By reference to Fig. 5, it will be seen that the two solenoids G' and G² are as usual provided with movable cores, and that these have stems g⁵ which support contact plates g⁸, these plates being insulated from the stems. Now when a core is raised as is shown at the right of the above mentioned figure, the stem and plate will be raised with it and the plate brought into electrical connection with each of the terminals on that solenoid. This, of course, puts all of these four terminals into electrical connection with each other, and any current leading to any one of them is free to pass to any of the others, and to any point with which any of them are in electrical communication. Therefore, when one of these plates is brought into contact with the four terminals, as described, the current is free to travel from the opposite automatic to the terminal g⁴, then across to the terminal g⁶, and from there to the fuse D', from which it takes a course through the lock solenoid E, and the direction solenoid is short-circuited and cut out. This does not affect the passage of the current through the main switch solenoid, however, as the terminal g³, which is in communication with the other terminals, is in connection, as has been stated, with the conductor leading to the opposite main switch solenoid, and, therefore, that is fed with current in the same way as it would have been if the direction solenoid had remained active, but the current is fed through a different path including the terminal g⁴.

The signal lamp I is employed to indicate to the operator the condition of the elevator.

It is convenient to have this lamp at full candle power when the car is in motion, and at half candle power when the car is stopped, provided the line is in condition to have it started, and to have it extinguished when the line is broken, as by the opening of a door, and the opening of one of the switches H', etc. In order to accomplish this, the plus main is connected through a signal lamp resistance i² in series with the signal lamp. The opposite side of the lamp is connected with the fuse D², which, as has been stated, is connected with the negative line through the door switches and the series resistance F. When the current passes in this way through the lamp, the lamp will burn at half candle power on account of the resistance in series with it, and if one of the door switches is opened, the current will, of course, be stopped and the lamp extinguished. In order to cause the lamp to burn at full candle power when the car is in motion, means are provided for shunting out the resistance i². This consists in a connection from the terminals g⁵ directly to the lamp I. When the car is in motion one of the terminals g⁵ is

connected by one of the plates g⁸ with one of the terminals g⁴, and consequently, the current is free to pass through the lamp, and it will burn at full candle power unless one of the door switches should be opened.

It has been seen that the passage of the current through one of the automatics A' or A² connects one of the direction switches B' or B² with the source of power, but that the connection is broken on account of these switches not being in contact with the terminals b³ or b⁴. I have provided means, which will be described below, for making one of these contacts when the operating handle is moved to send the car either up or down. If the car is to be sent up, one of these terminals is connected to the corresponding switch, and if it is to go down the other one is connected. In one case the current is then free to pass from the positive main through the down automatic A' to the switch B', the terminal b³ and then directly to the direction solenoid C'. In the other case the current can pass in a corresponding manner through the up automatic A² to the direction solenoid C² which sends the car up.

In order to supply current to the floor indicator K, the positive main is connected through a pair of well-room limit stops L' and L² with a pair of carbon terminals g⁹ and g¹⁰ on the main switch, one being adapted for operating when the car is to go up, and the other when the car is to go down. Both of these terminals when they are brought down into contact with the corresponding terminals g¹¹ and g¹² are thus brought into communication with a binding post M. These connections are represented in Fig. 2. Referring again to Fig. 3, it will be seen that this binding post is in constant communication with the fuse D². This fuse in turn communicates with a contact ring k' on the indicator. Pivoted within this contact ring is an indicating arm k² having a contact with the contact ring, and provided with a pointer k³ always in electrical connection with the contact ring. Located at equal distances from the center of the ring and the pivotal point of the pointer are a series of terminals representing the several floors. As shown in this figure there are five of these lettered n², n³, n⁴, a¹⁰ and a⁵, the last two being at the ends of the series. The terminals a¹⁰ and a⁵ are mounted on pivoted arms connected with the automatics A' and A². A spring is provided for holding the two terminals of each automatic in contact, and when the indicating arm moves around into a position to carry the pointer to engage either of the terminals a¹⁰ or a⁵ the corresponding arm is swung on its pivot and the conductor is broken at this point to open the circuit. When the pointer is in contact with one of the terminals n², n³ or n⁴, however, connection is made through the con-

ductors described from the binding post M , and, therefore, from the positive main through the pointer h^3 to the terminal, and from there to one of a series of contact plates 5 o^2 , o^3 and o^4 . These contact plates are located in the operating box in a series, corresponding to the number of floors, it being understood that at the two ends of the series 10 are plates o' and o^5 not in electrical connection with any part of the conducting system. These plates are inmounted in an arc or circle so that a pivoted pointer may be passed over them. This pointer is provided with a pair 15 of spring-pressed contacts, one of them being adapted to engage the terminals o' , o^2 , etc., in its passage over them, and the other to engage a contact segment b^5 . This segment is connected with the negative main at a point between the lock solenoid and the 20 resistance F . Therefore, it will be seen that when this pointer is in communication with any one of the terminals, except the two end ones, the current will be sent through the connections described above, as soon as the 25 indicating pointer h^3 comes into contact with the corresponding terminal on the indicator. This circuit is designed to short circuit the main switch solenoids and stop the car, and as the indicating pointer h^3 moves with the 30 car the latter will be stopped at the desired floor. At the ends of the travel of the car, it is stopped in a different way by the automatics A' and A^2 , and also the well-room limit stops L' and L^2 . 35 The conductor which connects the fuse D^2 with the ring h' is also connected with the rheostat solenoid P' . This is designed to operate connections for gradually throwing out resistance when starting the motor and 40 to protect it from a sudden rush of current. Referring to Fig. 2, it will be seen that the motor is provided with series and shunt windings, and that the binding post M is connected on one side with both. The binding 45 post is also connected with a terminal p' on the rheostat. The series winding is divided into two parts, the one nearer the binding post terminating in a conductor which is connected with a second terminal p^2 . The opposite end of the second half of 50 the series winding is connected with a third terminal p^3 . This terminal is also connected through a resistance q' with a terminal p^4 . In like manner this terminal is connected 55 through a resistance q^2 with a terminal p^5 which, through a resistance q^3 , is connected with a terminal p^6 , the latter through a resistance q^4 is connected with a binding post r . The binding post r is in series with a 60 movable contact blade g^{13} forming part of the main switch, and adapted to feed the motor as will be seen by the diagrammatic connections of Fig. 2. The blade g^{13} moves alternately to two contacts which feed the 65 armature of the motor in opposite directions.

In electrical connection with the binding post r is a pivoted arm p^7 on which are a plurality of contacts p^8 , all in electrical connection with the binding-post r . When the arm p^7 is raised current will pass from the 70 binding post M through the series winding through the resistances q' , q^2 , q^3 , q^4 to r and then to blade g^{13} . It is to be noted that the contacts p' , p^2 , p^3 , p^4 , p^5 and p^6 are arranged 75 in a step by step relation, each one being slightly raised by a spring above the one at the left, consequently, when the arm p^7 is lowered, one of the contacts p^8 comes in contact with the terminal p^5 . After this the current passes to the binding-post M through the 80 entire series winding to a binding post connected with the terminal p^8 , and from there through the resistances q' , q^2 and q^3 to the binding post r , and then around to the armature. As the resistance q^4 is now cut out or 85 short-circuited, there is less resistance in the line. As the terminals p^8 are lowered, the other terminals p^5 , p^4 and p^3 in their order are brought into electrical communication 90 with the binding-post r , and the resistances q^3 , q^2 and q' cut out by short circuiting. When the carbons p^8 are lowered another 95 step, the terminal p^2 is brought into connection with the binding post r , and one-half of the series winding is short circuited. When the terminal p^1 is brought into connection with the binding post r , the entire 100 series winding is short circuited and the motor is then run on the shunt alone. When the arm p^7 is raised, of course, the opposite 105 action takes place and the motor is started by use of the rheostat in a manner which will be readily understood. In connection with this diagram, it is to be noted that the armature is connected with another pair of terminals, and that a movable blade g^{14} similar to g^{13} vibrates between them. The carbon terminals g^9 , g^{10} , g^{11} and g^{12} are duplicated on the other side, a binding post M' taking the place of the binding post M , but 110 this one is not connected with the connections shown in Fig. 3. One other connection is shown on Fig. 3 which comprises a conductor between the switch D^2 and the car solenoid S . This solenoid is connected on 115 the other side with the negative main, and consequently, at all times when the binding post M is in circuit, the car solenoid will also be in circuit. This car solenoid is for the purpose of operating a contact to allow the elevator doors to be unlocked when the elevator stops opposite them, and to prevent their locking at other times. 120 In the course of the general description of the diagrammatic figures, a partial description of the mechanism employed has been given. Those features which have not been fully described will now be taken up in detail. 125 The slate which is shown in Fig. 4 con- 130

tains, as has been stated, the main switch G, the direction solenoid switches C' and C², the floor indicator K, the rheostat P, the fuse D', D² and D³, the line switch, and the 5 main fuses. The direction solenoid switches have been described in full. The main switch has also been described, and the way in which it operates the brake on the motor will now be taken up. Fig. 5 shows this 10 switch as provided with a rod g¹⁵ upon which are two ears having slots g¹⁶. The vibrating arms of the switch have studs g¹⁷ operating in said slots and moving the rod under certain conditions. The length of the 15 rod is adjustable in an obvious manner. At a certain point on the rod it is provided with a toggle-joint g¹⁸, the two ends of the toggle operating a pair of arms g¹⁹ which operate 20 brake-shoes g²⁰. These brake-shoes are pivotally mounted below the brake-wheel and may be lined with leather or other material to provide for an efficient operation. The arms g¹⁹ are normally forced together by a 25 strong spring g²¹ so that when the switch operates in such a manner as to permit the inner ends of the toggle arms to descend, the spring will operate to apply the brake. The position of the vibrating portion of the switch determines the condition of the brakes 30 as will readily be understood.

The floor indicator, as shown in Figs. 4, 8 and 9 is provided with any desired number of contacts, such as those represented by the characters n², n³, and n⁴ in Fig. 3. In the 35 other three figures mentioned, this indicator is shown as provided with a large number of contacts to enable the elevator to operate in a building with a corresponding number of floors. These contacts are connected in 40 the same manner as those represented in Fig. 3, and in fact, they represent the same thing.

As has been stated, the chain a' operates the floor indicator. This is done in the present instance, through a worm-wheel and 45 worm connected with a shaft k⁴. On this shaft is mounted a head k⁵ which is conveniently supported by a disk on the bearing for the shaft and which carries a ring k⁶. Under this ring is the stationary contact 50 ring k', and the ring k⁶ carries a pin k⁷ constantly in contact with the ring k'. The connections of the ring k' have been described above, and are shown in Fig. 3. This figure also shows the connections of 55 the contacts n', n², n³, etc. Each of these contacts is preferably provided with a roller, these rollers being set in the arc of a circle. The ring k⁶ carries a projection k⁸ which has a perforation through which passes a rod k⁹. 60 On this rod is a spring k¹⁰ for normally holding it in an extended position, and on its outer end it carries a contact k¹¹. This contact which is normally arranged in a 65 position to be engaged by the rollers, is provided with slanting surfaces from its center

so that the rollers may be adjusted on their support in such a manner as to regulate the length of time during which they will be in contact with this member. The supports for these rollers are intended to be adjusted 70 along the circular ring n on which they are mounted so as to make the car stopping circuit at exactly the right time to stop the car at the floor in each case. The length of time during which that contact is kept closed is 75 controlled by the position of the rollers, or the distance of the roller from the center of the circle. This point will, of course, be regulated by the weight of the car and other 80 mechanical considerations of a like nature. 80

It is to be observed that the projection k⁸ is provided with a socket for the part k¹¹ and on each side of the socket is an arm k¹² projecting in a slanting direction. These arms are designed for the purpose of engaging 85 the contact rollers on the up and down automatics A' and A² and for permitting them to pass the automatics under extraordinary conditions.

The rheostat shown in Figs. 10 and 11 has 90 previously been described in connection with the diagrammatic illustration of Fig. 2. The solenoid P' which operates it is connected in the manner shown in Fig. 3, and operates a plunger p⁹ that is pulled away 95 from the magnet by a spring p¹⁰, this plunger operating the arm p⁷ in an obvious manner, and dash-pots p¹¹ being provided for the usual purpose.

The operating box B has been referred to 100 several times. It has been stated that this operating box includes a lock solenoid E, and a pair of directing switches B' and B which are adapted to engage terminals b³ and b⁴. The contacts o', o², o³, etc., have 105 been mentioned, and the wiring has been described. It will be remembered that the contacts in this box, with the exception of the two at the ends, are connected with corresponding contacts which consist of rollers 110 in the floor indicator shown in Fig. 8, the number of contacts in each case being the same, and the end contacts not being connected together on account of the operation of the automatics A' and A². This operating box is designed for the purpose of 115 controlling the system. A handle or knob b⁶ is the only part of the mechanism which projects through the cover plate, and consequently the entire operation on the part of 120 the operator is performed through this hand-wheel. The cover-plate is intended to be opaque, and to conceal the parts within with the exception of a row of numbers indicating the floors and a pointer b⁷ passing 125 over these numbers. This pointer is controlled directly by the knob, and it is carried by an arm b⁸, preferably of insulating material. This arm is provided with a pair of 130 spring-pressed contacts b⁹, one of which con-

stantly engages the conducting ring b^5 which has been referred to in the description of Fig. 3. The other contact moves along in the path of the contacts o' , o^2 , o^3 , etc., and engages them in rotation. Consequently, as the two contacts b^9 are in constant electrical communication with each other, the connection between the strip b^6 and the contact over which the arm rests 10 will be made to produce the effects which have been previously described.

In order to operate the arm b^8 from the knob b^6 , the latter is provided with a collar b^{10} having a projection b^{11} . This collar is 15 mounted rigidly on the shaft which carries the wheel, and this is the only part which is rigid at all times with the hand-wheel. The arm b^8 is mounted in a frame b^{12} which is capable of rotation in bearings provided 20 within the box. It will not rotate upon the turning of the hand-wheel b^6 , however, unless the projection b^{11} is in engagement with the arm b^8 , as shown in Fig. 14. When this is the case, the arm and pointer will go 25 with the hand-wheel, otherwise the hand-wheel may be turned without causing any motion of the pointer.

The direction switches are so connected with the direction solenoids as to determine 30 the direction in which the car shall move. Consequently, it is desirable that when the pointer is moved sufficiently to cause the car to move to any floor, the corresponding direction switch should be operated thereby, 35 and that the switch should be opened immediately after the car starts in order that it may be in proper condition to start the car in the same direction or to return it. It will be remembered that the solenoid direction switches C' and C^2 are also thrown out 40 of connection immediately after they have performed their duties. To secure this result, in this case a clutch is provided, comprising a friction surface on the frame and 45 a friction plate b^{13} mounted to turn on the same axis, and provided with a friction plate engaging said friction surface. This friction plate has a lug b^{14} which is adapted to engage either of the switch arms B' or B^2 50 and move them into engagement with the terminals b^3 and b^4 against the resistance of a spring b^{15} . Now if no pressure is applied to the back of the plate b^{13} , the movement of the frame b^{12} will not result in imparting 55 motion of the former. In order to apply friction at this point, and in fact to concentrate all the friction here, a plate b^{16} is provided which is movable along a hub on the frame b^{12} . This plate has roller bearings between it, and the back of the plate b^{13} and a bell-crank b^{17} , shown in Fig. 18, 60 is provided for forcing the plate against the friction plate. This bell-crank has a connection with a reciprocable locking stud e' 65 connected with the lock solenoid. This stud

is provided with a head for engaging the bell-crank and forcing the plate b^{16} toward the friction plate, and when the parts are in position shown in Fig. 15, the friction plate will move with the frame b^{12} , and performs its ordinary function. 70

The stud e' is normally held down in the position indicated in Fig. 14 by means of a spring e^2 , and it is connected with a core e^3 in the solenoid which upon the excitation 75 of the latter, will move the stud upwardly into position to relieve the tension of the spring, and thus allow the bell-crank to turn and the plate b^{16} to move backward a slight distance so as to relieve the frame b^{12} of the 80 friction. This frame can now turn without causing the friction plate to turn, and without moving the direction switches. Another function which the stud possesses and which gives the name to this part of the 85 mechanism is that the head in normal position is out of the path of the projection b^{11} , but when projected upwardly by the solenoid, is in the path of this projection, and will prevent its passing beyond it. Consequently, when the pointer is placed in any 90 certain position and the solenoid is actuated, the hand-wheel can be turned in the opposite direction far enough to bring the projection b^{11} into contact with the other side 95 of the arm b^8 , and therefore, this arm and the pointer cannot be moved in the opposite direction until the pin e' has been withdrawn by the spring e^2 . In order for this to take place the current has to be cut off 100 from the solenoid, as by operation of one of the automatics.

It is intended that the operation of the contacts on the arm b^8 shall be the same throughout the system, but it is found in 105 practice that if the arm is stopped near the end of the next to the last contact, it does not have space enough to move to accomplish the desired result in moving onto the last contact, therefore, I have provided this 110 arm with a pair of metallic pointed projections b^{18} . One of these projections is adapted to come into contact with two posts b^{19} when the arm reaches the end of its travel in either direction. These two posts are insulated from each other, and one is connected with the terminal b^3 while the other is connected with the switch member B' . On the other side, similar connections 115 are made with the terminal b^4 and member B^2 . Consequently, if the projection b^{14} does not move far enough to bring the arm B' or B^2 into contact with the terminal b^3 or b^4 , the movement of the arm to the limit of its stroke will perform the same function by 120 connecting these elements through the projections b^{18} and the posts b^{19} . The manner in which these parts operate has been described above. 125

Referring now to Fig. 19, it will be seen 130

that the car solenoid S, the connections of which have been described before, is provided with a plunger s' operating a reciprocable rod s^2 . This rod is pivotally connected with a pair of bell-cranks s^3 , which, at their opposite ends, carry a rail s^4 . A spring s^5 is provided for normally forcing the rail outwardly in opposition to the action of the solenoid S. Now at each door 10 there is a lock T having a bolt t' with which is connected a lever t^2 carrying a roller t^3 . A spring t^4 normally forces the bolt into locking position, and the roller into the path of the rail s^4 , when the latter is projected by the spring connected with it. When the parts are in the position indicated in Fig. 19; that is, when the solenoid S is energized as it is during the travel of the car, the rail is thrown back into a position 20 such that it will not engage the several rollers t^3 , but when the car stops, the solenoid S is cut out and, therefore, the spring s^5 is free to force the rail s^4 against the roller t^3 at the floor at which the car stops. 25 This swings the lever and unlocks the door so that it can be opened. In this figure, also is shown a detail of one of the contacts H'. This comprises a pair of spring-pressed pivoted contact members h' connected with the line between the fuse D^3 and the line passing to the resistance F, as shown in Fig. 3. A contact plug h^2 is mounted on an insulating plate in such position that when the door closes, the ends of 30 the two members h' will engage it and both of them make a contact with it. When the door is opened, they are withdrawn from the plug and the contact is broken in an obvious manner. 35 On the car also is shown a box U having push buttons representing the several floors. This is a part of the annunciating system which has been referred to above. At each door, also, there is a press button, not shown, 40 also constituting a part of this annunciating system and constructed in any ordinary manner.

By referring to the first part of this specification, the general manner of operation of the system as a whole will be understood. The description of the several parts which has been given shows how these parts coöperate in order to provide the desired results. 50 While I have shown and described a particular form in which my invention may conveniently and efficiently be embodied, I am aware that many modifications may be made therein, not only in the construction 55 of the several features which are combined to form the system, but in the arrangement thereof, and, therefore, in the system itself, by any person skilled in the art without departing from the spirit of the invention as 60 expressed in the claims.

Having thus fully described my invention, what I claim and desire to secure by Letters Patent is:—

1. In an elevator system, the combination of a hoisting machine, a series of 70 doors, an operating box having a movable pointer arm, a knob or handle for moving the pointer arm, and electrical means for controlling the entire operation of the hoisting machine directly from said pointer arm, 75 comprising connections whereby when one of said doors is open the electrical means will be inoperative to start the hoisting machine.

2. In an elevator system, the combination of a hoisting machine, a movable pointer arm, an operating knob or handle for moving the pointer arm, movable independently of the pointer arm, means controlled by said pointer arm for starting the 80 hoisting machine in either direction and for stopping it, an operating box inclosing said means, a series of doors, and means whereby when any one of said doors is open the hoisting machine will be rendered inoperative. 90

3. In an elevator system, the combination of a car, a rotatable knob or handle for controlling the destination of the car, means controlled by the knob or handle for 95 starting the car, and magnetic means for positively locking the knob or handle against reverse motion after it has started to move in either direction.

4. In an elevator system, the combination 100 of a car, a pointer arm for controlling the destination of the car, means for starting the car, means for stopping the car at the floor indicated by the pointer arm, and an electromagnetic means operating when the 105 pointer arm is started in either direction for automatically locking the pointer arm against reverse motion.

5. In an elevator system, the combination 110 of an operating mechanism comprising a knob or handle and means connected with said knob or handle for directly controlling the entire operation of a hoisting machine, with a floor indicator connected with said operating mechanism and constituting means for closing stopping circuits at the floors. 115

6. In an elevator system, the combination 120 of an operating mechanism, a motor, means connected with the operating mechanism for directly controlling the operation of the motor, a series of motor stopping circuits, and a floor indicator connected with said operating mechanism and constituting means for closing the motor stopping circuits at the several floors of the elevator well. 125

7. In an elevator system, the combination 130 of an operating mechanism, a motor controlled thereby, a floor indicator having a

- series of contacts, one representing each floor of the elevator well, said operating mechanism having a corresponding series of contacts electrically connected with the corresponding contacts in the floor indicator, said operating mechanism comprising a movable member adapted to connect any desired one of the contacts therein with a power supplying main, said floor indicator comprising a movable member adapted to engage the several contacts therein and electrically connected with the other power supplying main, each of the connections between the contact of the indicator and controlling mechanism constituting means for short-circuiting a motor-controlling circuit. 5
8. In an elevator system, the combination of a car, operating mechanism therefor, a controlling mechanism mechanically independent of the operating mechanism but electrically connected therewith comprising a movable member, which by its position determines the floor at which the elevator car is to stop, with a floor indicator having a movable member, means for controlling the stopping of the car, and means for causing the last named movable member to travel proportionately to the travel of the car. 20
9. In an elevator system, the combination of a car, a controlling mechanism comprising a movable member, which by its position determines the floor at which the elevator car is to stop, with a floor indicator having a movable member, means for causing the last named movable member to travel proportionately to the travel of the car, and a plurality of motor stopping circuits one being closed at one point by the first named movable member when it indicates a floor, and all being closed in turn at another point by the second movable member as the car passes the several floors. 25
10. In an elevator system, the combination of a car, a controlling mechanism and a single means for operating said controlling mechanism, said controlling mechanism comprising a movable member which by its position determines the floor at which the elevator car will stop, with a floor indicator having a movable member, means for causing the last named movable member to travel proportionately to the travel of the car, a series of contacts representing the several floors, and means for closing a motor stopping circuit as said last named member passes each of said series of contacts. 30
11. In an elevator system, the combination of a car, a controlling mechanism comprising a series of contacts, a movable member adapted to move over said contacts to engage the one indicating the floor to which the elevator car is to move, and to close a corresponding motor stopping circuit, with a floor indicator comprising a corresponding series of contacts, a movable member, 35
- means for moving said member in proportion to the movement of the car, said member representing the car at all times and showing its position, and means connected with the contacts of said floor indicator for closing a motor stopping circuit as the movable member passes each contact and as the car passes each floor, each of said motor stopping circuits being broken at the controlling mechanism except the one closed by the movable member thereof. 40
12. In an elevator system, the combination of a car, a controlling mechanism comprising a pair of direction switches and a controlling handle or knob having means for closing either of said switches in accordance with the direction of movement of the handle or knob, with a pair of direction solenoid switches connected with said switches in the controlling mechanism, and means connected with said direction solenoid switches for controlling the direction of movement of the elevator car, and means for automatically opening said direction switches. 45
13. In an elevator system, the combination of a car, a controlling mechanism comprising a pair of direction switches and a controlling handle or knob having means for closing either of said switches in accordance with the direction of movement of the handle or knob, with a pair of direction solenoid switches connected with said switches in the controlling mechanism, means connected with said direction solenoid switches for controlling the direction of movement of the elevator car. 50
14. In an elevator system, the combination of a car, a controlling mechanism comprising a pair of direction switches, and means for closing either of said switches, with a pair of direction solenoid switches connected with said switches in the controlling mechanism, and means connected with said direction solenoid switches for controlling the direction of movement of the elevator car. 55
15. In an elevator system, the combination of a controlling mechanism comprising a pair of direction switches, and means for closing either of said switches with a pair of direction solenoid switches and electric circuits connecting each of the solenoid switches with one of said switches in the controlling mechanism. 60
16. In an elevator system, the combination of a controlling mechanism comprising a pair of direction switches, a pair of direction solenoid switches electrically connected therewith and operated thereby, and a main switch having two parts for controlling the direction of motion of the elevator car, said parts each having a solenoid connected with one of the direction switch solenoids. 65
17. In an elevator system, the combination of a controlling mechanism, a main switch having solenoids for controlling the direction of motion of the elevator car. 70

- tion of motion of the car, means for connecting said solenoids with a source of electrical energy comprising a pair of direction solenoid switches, and means for shunting 5 the direction solenoid switches out of the circuit after they have connected one of the main switch solenoids with a source of power, and thus giving direction to the motion of the elevator car, and for leaving one 10 of the main switch solenoids in the circuit.
18. In an elevator system, the combination of a controlling mechanism, a pair of direction solenoid switches, electrical connections from the controlling mechanism to 15 said switches, a main switch having two solenoids, connections from each of said direction switch solenoids to one of said main switch solenoids, said direction solenoid switches each having means for opening the 20 last named connections when the solenoid of the direction switch is deenergized, and the main switch having means for supplying current to one of its solenoids through another path when the other solenoid is de- 25 energized.
19. In an elevator system, the combination of a pair of direction solenoid switches, a main switch having two solenoids connected to operate alternately, a connection from 30 each of the direction solenoids to one of the main switch solenoids for supplying current thereto, the direction switches having means for breaking said connection when the direction solenoids are deenergized, and means 35 connected with the armature of each of the main switches for providing connections for the supplying of current to the opposite main switch solenoid.
20. In an elevator system, the combination 40 of a direction solenoid switch, a main switch having a solenoid, a connection from the direction solenoid to the main switch solenoid for supplying current thereto, the direction switch having means for breaking said connection when the direction solenoid is de- 45 energized, and means connected with the main switch for providing connections for the supply of current to the main switch solenoid independently of the direction 50 switch solenoid.
21. In an elevator system, the combination with a car, a down automatic, and an up automatic each connected in series with a main 55 for supplying current, said automatics being adapted to break the circuit, of a main switch having two solenoids, one connected in series with each of said automatics, said solenoids also being connected with the other power supplying main and a floor indicator 60 adapted to stop the car at any intermediate floor by making a circuit and to operate said up and down automatics to break this circuit.
22. In an elevator system, the combination 65 of a direction switch, a magnetically controlled controller lock, and automatic limit stops in series with said switch said lock being connected with the line by said switch, whereby the switch and lock are rendered inoperative when the stops are opened. 70
23. In an elevator system, the combination of a car, direction switches, a magnetically controlled lock for preventing reversal of the direction of motion of the elevator car, a pair of automatic limit stops each in 75 series with the lock and with one of said switches, whereby when one of said limit stops is opened, the corresponding switch and the lock will be rendered inoperative.
24. In an elevator system, the combination 80 of a movable controlling member, direction switches, means loosely connected with said member for closing said switches, a magnetically controlled lock for locking said means with respect to said member, a series of door 85 switches, and means for operating said lock when any one of said door switches is open.
25. In an elevator system, the combination 90 of a series of door switches, a pair of direction switches, means for controlling the direction switches, a magnetically controlled lock for locking the controlling means against reverse motion, and means for operating said lock whether the door switches are open or closed and for unlocking it by 95 the opening of a door switch.
26. In an elevator system, the combination 100 of a series of door switches, a car, means for controlling the operation of the car, a magnetically controlled lock for locking the controlling means against motion, means for operating said lock while the door switches are open or closed, and means whereby the opening of a door switch will unlock said 105 controlling means.
27. In an elevator system, the combination 110 of direction switches, means for closing said switches, a car, a signal lamp, means for sending a current through the lamp when either of the switches is closed, and means for sending a current of different strength through the lamp when said car is stopped and ready for operation.
28. In an elevator system, the combination 115 of a signal lamp, a car, means for burning the lamp at full candle power when the car is in motion, and means for burning the lamp at reduced candle power when the car is stopped and in condition for operation.
29. In an elevator system, the combination 120 of a signal lamp, means for burning said lamp at full candle power when the elevator car is in motion, means for burning the lamp at reduced candle power when the car is stopped but in condition for operation, and means for extinguishing the lamp when the motor controlling circuit is interrupted. 125
30. In an elevator system, the combination 130 of direction switches, means for closing said switches, a signal device, means for conduct-

ing a current to said signal device when either of the switches is closed, controlled by said switches, and means for opening the direction switches after they are closed.

5 31. In an elevator system, the combination of direction switches, means for closing said switches, a signal lamp, means for sending a current through said lamp when either of said switches is closed, means for immediately opening the direction switches after they are closed, and means for continuing the supply of current to the lamp.

32. In an elevator system, the combination of direction switches, means for closing said switches, direction solenoid switches supplied with current through said direction switches when they are closed, a signal lamp, and means controlled by the direction solenoid switches for sending a current through 20 the lamp.

33. In an elevator system, the combination of direction switches, means for closing said switches, direction solenoid switches supplied with current through said direction switches when they are closed, a main switch, a signal lamp, and means controlled by the main switch for sending a current through 25 said lamp.

34. In an elevator system, the combination of a main switch having a solenoid for operating it, means for connecting said solenoid with a pair of power supplying mains, a plurality of door switches in series with said solenoid whereby the opening of a door 30 in the elevator well will break the circuit, a signal lamp, means for connecting the signal lamp with one of said mains through a resistance, and means for connecting the opposite side of the signal lamp in series 35 through said door switches with the other main.

35. In an elevator system, the combination of a main switch having a solenoid, means for connecting said solenoid with a pair of power supplying mains, a signal lamp, means for connecting the signal lamp with one of said mains through a resistance, means for connecting the opposite side of the signal lamp with the other main, and means for 40 connecting the first main directly with the signal lamp to shunt out said resistance when the solenoid of the main switch is energized.

36. In an elevator system, the combination of a main switch having a solenoid for operating it, means for connecting said solenoid with a pair of power supplying mains, a plurality of door switches in series with said solenoid whereby the opening of a door in the elevator well will break the circuit, a signal lamp, means for connecting the signal lamp with one of said mains through a resistance, means for connecting the opposite side of the signal lamp in series through 45 said door switches with the other main, and means for connecting the first main directly 50

with the signal lamp to shunt out said resistance when the solenoid of the main switch is energized.

37. In an elevator system, the combination of a main switch comprising two solenoids one adapted to control a hoisting machine to run it in one direction and the other to control it to run in the other, means for connecting one terminal of each of said solenoids with a main for supplying power, 75 means for connecting the opposite terminals of the two solenoids with the other main, said last named means comprising a plurality of switches in series, each one adapted to break the circuit through the main switch 80 solenoid, a signal lamp, means for connecting the first named main to the signal lamp through a resistance, means for connecting the other side of the signal lamp with said plurality of switches whereby the lamp will 85 burn at partial candle power when said switches are closed and when the main switch is deenergized, and means for connecting the circuit feeding the main switch solenoids directly with the signal lamp when 90 either of said solenoids is energized to burn the signal lamp at full candle power.

38. In an elevator system, the combination of a main switch comprising two solenoids one adapted to control a hoisting machine to run it in one direction and the other to control it to run in the other, means for connecting one terminal of each of said solenoids with a main for supplying power, 95 means for connecting the opposite terminals of the two solenoids with the other main, said last named means including a plurality of switches in series, each one adapted to break the circuit through the main switch solenoid, a signal lamp, means for connecting the first named main to the signal lamp through a resistance, means for connecting the other side of the signal lamp with said 100 plurality of switches whereby the lamp will burn at partial candle power when said switches are closed and when the main switch is deenergized, means for connecting the circuit feeding the main switch solenoids directly with the signal lamp when either of said solenoids is energized to burn the signal lamp at full candle power, and a rheostat 105 operated by a solenoid connected in series with said binding post and the other main.

39. In an elevator system, the combination of a controlling mechanism comprising a series of contacts representing several floors of the elevator well, an arm adapted to move over said contacts, a conductor constantly connecting said arm with a main for supplying power, and means located outside the controlling mechanism for making a motor stopping circuit through each of said contacts as the elevator car passes the several floors.

40. In an elevator system, the combination of a controlling mechanism comprising a series of contacts representing several floors of the elevator well, an arm adapted to move over said contacts, a conductor constantly connecting said arm with a main for supplying power, means located outside the controlling mechanism for making a motor stopping circuit through each of said contacts as the elevator car passes the several floors, and means controlled by said controlling mechanism for moving the elevator car in either direction.

41. An elevator system comprising a controlling mechanism, said controlling mechanism comprising a series of contacts arranged in position for engagement by a movable member thereof, a conductor in constant electrical communication with said movable member, a pair of direction switches, means connected with the movable member for operating one of said direction switches whenever the member is started to move in either direction, and means for releasing said direction switches and breaking the contact made by them.

42. A controlling mechanism for an elevator system comprising a manually operable knob or handle, a projection secured thereto, an arm concentrically mounted with respect to said knob and movable therewith when the projection engages it, and electrical devices connected with said arm for controlling the entire operation of a motor.

43. A controlling mechanism for an elevator system comprising a rotatable knob or handle mounted to swing about an axis and having a projection, an arm mounted independently of the knob to turn on the same axis and movable by the knob only when the projection engages the arm, and electrical connections connected with the arm for controlling the operation of a motor.

44. A controlling mechanism for an elevator system comprising a rotatable knob or handle mounted to swing about an axis, an arm mounted to turn on the same axis and movable by the knob, electrical connections connected with the arm for controlling the operation of a motor, and means for preventing the rotation of said handle beyond a certain point in a direction contrary to that in which it is started.

45. A controlling mechanism for an elevator car system comprising a manually operable knob or handle, an arm concentrically mounted with respect to said knob and movable therewith, electrical connections carried by said arm for controlling the entire operation of a motor for operating the car, means for preventing the motion of the arm in a backward direction after it has been once moved in either direction, and means for rendering the last named means

inoperative when the car has moved to the floor indicated by the position of said arm.

46. A controlling mechanism for an elevator system, comprising a pointer, an electric switch connected therewith, means loosely connected with the pointer for actuating it, a lock, and means for actuating the lock for preventing reverse motion of the pointer after it has been started to move in either direction.

47. A controlling mechanism for an elevator system comprising a controlling arm, a series of contacts with which said arm is adapted to engage, each contact representing a floor in the elevator well, means for moving said arm along said contacts, and means for preventing the arm from moving back after it has started in either direction until the elevator car has moved to and stopped at the floor indicated by said arm.

48. A controlling mechanism for an elevator system comprising a controlling arm, a series of contacts with which said arm is adapted to engage, each contact representing a floor in the elevator well, means for moving said arm along said contact, means for preventing the arm from moving back after it has started in either direction until the elevator car has moved to the floor indicated by said arm, said last named means comprising a solenoid located in a motor controlling circuit in parallel with the motor circuit, and means for short-circuiting the circuit in which said solenoid is located to stop the motor, said solenoid having an armature provided with a stud or pin adapted to project into a position to prevent motion of said arm in a certain direction when the solenoid is energized.

49. A controlling mechanism for an elevator system comprising a rotatable knob or handle having a projection, a controlling arm adapted to be moved by said projection, a frame on which said controlling arm is mounted, a member loosely mounted on the axis on which the controlling arm turns, said member having a projection, means for transmitting motion from the frame to said member, and a pair of direction switches located in the path of said projections whereby the movement of the arm in either direction will transmit motion through the member to one of said switches to close it.

50. A controlling mechanism for an elevator system comprising an oscillatable frame having a pointer thereon and provided with electrical connections, a clutch having a projection, a pair of direction switches, each having a movable arm located in the path of said projection, and means for forcing the clutch into operative condition whereby motion of the frame in either direction will be transmitted to the projection and the latter will move the arm of one of said switches.

51. A controlling mechanism for an elevator system comprising an oscillatable frame having a friction surface, a friction disk mounted adjacent to said surface, a pair of direction switches, said friction disk having means for closing said switches, a plate having anti-friction bearings located behind said disk, and means for forcing said plate toward the disk whereby the friction surface 5 of said frame and disk will come into close contact and the movements of the frame will be transmitted to the disk.
52. In a controlling mechanism for an elevator system, the combination of an oscillatable frame, a pair of direction switches, a friction disk located adjacent to said frame and provided with means for closing said switches, a plate bearing on the back of said disk for forcing it into frictional engagement with the frame, a bell-crank for operating said plate, a headed stud for engaging said bell-crank and operating it, a spring for moving said stud into operative position, and a solenoid for releasing said stud 20 and permitting the frame to move without transmitting motion to the disk.
53. In a controlling mechanism for an elevator system, the combination of an oscillatable frame, a pair of direction switches, a friction disk located adjacent to said frame and provided with means for closing said switches, a plate bearing on the back of said disk for forcing it into frictional engagement with the frame, a bell-crank for operating said plate, a headed stud for engaging said bell-crank and operating it, a spring for moving said stud into operative position, and a solenoid for releasing said stud 25 and permitting the frame to move without transmitting motion to the disk.
54. In a controlling mechanism for an elevator system, the combination of an operating knob or handle, a frame movable thereby, a pair of direction switches, means connected with said frame for closing said direction switches and means for rendering the closing means operative independently of the position of the operating knob and for preventing the movement of the frame, in a direction contrary to its last movement when said switch closing means is inoperative.
55. A controlling mechanism comprising an oscillatable frame, a pair of direction switches located adjacent thereto, means connected with the frame for closing one of said switches when the frame commences to turn, and means for thereafter releasing the closing means whereby the frame can continue to turn without further affecting the switches.
56. A controlling mechanism comprising an oscillatable frame, a pair of direction switches, means connected with the frame for closing one of said switches when the frame commences to turn, and means for 70 then opening the switch and keeping it open during the remainder of the movement of the frame.
57. A controlling mechanism for an elevator system, comprising a movable controlling member, direction switches, means loosely connected with said member for closing said switches, and a magnetically controlled lock for locking said means with respect to said member.
58. In a controlling mechanism for an elevator system, the combination of a switch, a rotatable knob or handle, means frictionally connected therewith for closing the switch, means for preventing the reverse 85 movement of the handle or knob beyond a certain point, and means for simultaneously retracting the last named means and applying pressure to the main switch closing means to render the latter operative.
59. In an elevator system, the combination of direction switches, a rotatable knob or handle, means frictionally connected therewith for closing a switch, means for preventing the reverse movement of the handle 95 or knob beyond a certain point, means for simultaneously retracting the last named means and applying pressure to the switch closing means to render the latter operative, a pair of direction solenoid switches, said 100 direction switches having means for supplying current to the solenoids of the solenoid switches, and a main switch comprising a pair of solenoids, the solenoid switches having means for feeding current to said main 105 switch solenoids, said main switch comprising a pair of armatures for said solenoids, a rocking frame, the armatures being connected with the opposite sides of said frame.
60. A main switch for an elevator system 110 comprising a pair of solenoids, a rocking frame, armatures for said solenoids connected with said frame on opposite sides of its pivotal point, a rod depending from each armature, a contacting plate mounted on each 115 rod and insulated therefrom, and four contacting terminals located below the solenoid in position to be engaged by said plate and electrically connected with each other through said plate when the armature by 120 which that plate is supported is moved outwardly from its solenoid.
61. In a switch the combination of a pair of solenoids each having an armature, a rocking frame connected with said armatures on opposite sides of its pivotal point whereby the movement of one armature in one direction will cause the other to move in the other direction, four terminals located below each solenoid, two of the terminals of 130

one solenoid having direct electrical connection with the corresponding two terminals of the other, one terminal of each solenoid being in communication with a source 5 of power, and the fourth terminal of each solenoid being in direct connection with a conductor for supplying power to the other solenoid, and means connected with each armature for connecting all four terminals to 10 its solenoid.

62. A switch for an electrical elevator system comprising a pair of solenoids, a pair of armatures therefor movable alternately, a pair of terminals supported adjacent to each 15 solenoid, one of said terminals of each pair being in constant communication with a source of electrical energy, the other terminal of each pair being in constant communication with a conductor leading to the 20 opposite solenoid, and means connected with each armature for connecting the two terminals mounted adjacent to its solenoid when the same is deenergized, and the armature withdrawn.

63. A switch for an electrical elevator system comprising a pair of solenoids, a pair of armatures therefor movable alternately, a pair of terminals supported adjacent to each solenoid, one of said terminals of each 25 pair being in constant communication with a source of electrical energy, the other terminal of each pair being in constant communication with a conductor leading to the opposite solenoid, means connected with each 30 armature for connecting the two terminals mounted adjacent to its solenoid when the same is deenergized and the armature withdrawn, a motor having a brake wheel, brake shoes for said brake-wheel, and means 35 connected with said switch for forcing said 40 brake-shoes against the brake-wheel.

64. In an electrical elevator system, the combination of a switch comprising a pair of solenoids, a rocking frame, a pair of armatures for said solenoids connected with 45 said frame, on opposite sides of its pivotal point, a motor a brake therefor, and means operable by the movement of said frame for applying said brake.

65. A switch for an electric elevator system comprising a pair of solenoids, each having an armature, a rocking frame with which the armatures are connected on opposite sides of its pivotal point, a rod connected with said frame, a toggle lever connected with said rod, and a pair of brake-shoes operable by the movements of said rod as transmitted through said toggle lever.

66. In an electric elevator system, the combination of a motor, a binding post connected with a main for supplying current, said motor being connected with said binding post, a rheostat solenoid for the motor connected with said binding post in parallel 50 with the motor, and a floor indicator con-

nected with the binding post in parallel with the rheostat.

67. In an electric elevator system, the combination of a motor, a binding post connected with a main for supplying current, said motor being connected with said binding post, a rheostat solenoid for the motor connected with said binding post in parallel with the motor, a floor indicator connected with the binding post in parallel with the 75 rheostat, said floor indicator comprising a conducting ring connected directly with said binding post, a rotatable arm having constant electrical connection with said ring, said arm having a conducting pointer at its 80 end, and a series of contacts adapted to be engaged by said arm during its movement, said contacts having connections for stopping the motor.

68. In a floor indicator for an electric elevator system, the combination of a conducting ring connected with a source of power, a rotatable element, means for electrically connecting said element with said ring, a projection on said rotatable element, a spring-pressed contact member located on 90 said projection, and a series of contacts with which said spring-pressed member is adapted to engage.

69. A floor indicator for an electric elevator system, comprising a conducting strip connected with a source of electrical energy, a movable member having means for constantly connecting it with said strip, and a resiliently mounted contact member supported 100 on said movable member and adapted to engage a series of stationary contacts.

70. A floor indicator for an electric elevator system comprising a rotatable element having a projection thereon, means for constantly connecting said element with a source of electrical energy, a contact head mounted on said projection and provided with sloping surfaces, a spring for forcing 110 said contact head outwardly, and a series of 110 stationary adjustable contact members located in the path of said head.

71. A floor indicator for an electric elevator system, comprising a rotatable element, means for constantly connecting said 115 element with a source of electrical energy, a contact head resiliently mounted on said element and provided with sloping surfaces, a pair of sloping arms extending outwardly from said head and fixed in stationary position with respect to said rotatable element, and a series of contacts located in the path of the sloping surfaces of said head.

72. A floor indicator for an electric elevator system, comprising a rotatable element, 125 a contact head resiliently mounted on said element and provided with sloping surfaces, a pair of sloping arms extending outwardly from said head and fixed in stationary position with respect to said rotatable element, 130

- and a series of contacts located in the path of the sloping surfaces of said head.
73. A floor indicator for an electric elevator system comprising a rotatable element having a projection thereon, a contact head mounted on said projection and provided with sloping surfaces, a spring for forcing said contact head outwardly, and a series of stationary adjustable contact members located in the path of said head.
74. A floor indicator for an electric elevator system comprising a rotatable element constantly connected with a power supplying main, a head on said element, a pair of sloping arms on the element adjacent to said head.
75. A floor indicator for an electric elevator system comprising a rotatable element constantly connected with a power supplying main, a head on said element, a pair of sloping arms on the element adjacent to said head, a series of contacts located in the path of said head, and a pair of automatics for breaking the circuit having projections located in the path of said arms.
76. A floor indicator for an electric elevator system comprising a movable resiliently mounted head connected with a power supplying main, a series of contacts adjustably mounted in the path of said head, each contact comprising a roller, and each contact being in electrical communication with means for short-circuiting a motor controlling circuit.
77. A floor indicator for an electric elevator system comprising a movable resiliently mounted head connected with a power supplying main, a series of contacts adjustably mounted in the path of said head, each contact comprising a roller, each contact being in electrical communication with means for short-circuiting the motor for operating the elevator, and said head being provided with sloping surfaces whereby the duration of contact between the rollers and head can be regulated.
78. A floor indicator for an electric elevator system comprising a movable resiliently mounted head connected with a power supplying main, a series of contacts adjustably mounted in the path of said head, each contact comprising a roller in electrical communication with means for short-circuiting a motor controlling circuit, and a pair of automatics connected in series with a power supplying circuit, said automatics having projections located in a position to be operated when the head reaches a limiting position.
79. In an electric elevator system, the combination of a motor, a controller therefor, a rotatable element connected with said controller, means connected with the motor for rotating said element in proportion to the movement of the motor, and also in pro-

portion to the movement of the elevator car, said rotatable element having means for indicating at all times the position of the car.

80. In an electric elevator system, the combination of a motor, a controller therefor, a rotatable element connected with said controller and having a pointer, a chain and sprocket connection between the motor and the rotatable element for rotating the latter in proportion to the rotation of the armature of the motor whereby the pointer may indicate at all times the position of the elevator car.

81. In an elevator system, the combination of a motor, a switch for controlling the operation of the motor comprising contact members rockable on an axis and projecting in opposite directions therefrom, a brake for the motor, and a rod for operating said brake connected with, and operated by, said switch.

82. In an elevator system, the combination of a motor, a switch for controlling the operation of the motor comprising a rock shaft and arms projecting therefrom in opposite directions, contact members, contact members on said arms adapted to engage the other contact members, a brake wheel on the motor shaft, a brake for said wheel, a reciprocating rod connected with said brake, and means connected with said shaft for operating said rod and brake.

83. In an elevator system, the combination of a motor, a switch for controlling the operation of the motor comprising a rock shaft and arms projecting therefrom in opposite directions, a plate having contact members thereon, contact members on said arms adapted to engage the other contact members on the plate, a brake wheel on the motor shaft, a brake for said wheel located below said plate, a vertically reciprocating rod extending down through said plate and connected with said brake, and means connected with said shaft for operating said rod and brake.

84. In an elevator system, the combination of a motor, a brake-wheel connected therewith, a pair of brake shoes pivotally mounted near the bottom of said wheel and projecting upwardly on opposite sides thereof, resilient means for normally forcing said brake shoes toward the wheel, a toggle connecting the upper ends of said brake shoes, a rod connected with said toggle and projecting therefrom, a switch for controlling the operation of the motor, and means connected with said switch for operating said rod.

85. In an elevator system, the combination of direction switches, means for closing said switches, a signal lamp, and means for sending a current through said lamp and simultaneously rendering the switch clos-

ing means inoperative, whereby said switches are returned to open position.

86. In an elevator system, the combination of direction switches, means for closing 5 said switches, a signal lamp, and means for sending a current through said lamp and simultaneously rendering the switch closing means inoperative, and at the same time causing said lamp to burn at full candle power.

87. In an elevator system, the combination of direction switches, means for closing 10 said switches, direction solenoid switches

supplied with current through said direction switches when they are closed, a main switch, a signal, and means controlled by the main switch for sending a current through said signal.

In testimony whereof I have hereunto set 20 my hand, in the presence of two subscribing witnesses.

EDWARD L. DUNN.

Witnesses:

ALBERT E. FAY,
CATHARINE I. HARTNETT.
